(Cl. D42—8)

To all whom it may concern:

Be it known that I, Otto Grun, a citizen of the United States, residing in the Borough of Manhattan, city, county, and State of New York, have invented a new, original, and ornamental Design for a Combination Golfer's Watch and Tee Holder Unit, of which the following is a specification, reference being had to the accompanying drawing, forming part thereof.

On the drawing,

Fig. 1 is a front elevational view of a combination golfer's watch and tee holder unit, showing the essential features of my new design in full lines, and as it appears when mounted upon a belt while in use;

Fig. 2 is a side elevational view of the combination golfer's watch and tee holder unit shown in Fig. 1;

Fig. 3 is a rear elevational view of the combination golfer's watch and tee holder unit shown in Fig. 1;

Fig. 4 is a front elevational view of my design as it appears when not in use and expanded to its full length; and

Fig. 5 is a rear elevational view of the design as it was shown in Fig. 4.

The essential features of my design for a combination golfer's watch and tee holder unit reside in the specific configuration of the same, and include the arrangement of the golf tees, the fragments of a belt shown in Figs. 1, 2 and 3 being for illustrative purposes only.

I claim:

The ornamental design for a combination golfer's watch and tee holder unit, substantially as shown and described.
